UNITED STATES PATENT OFFICE.

FRANK M. PIERCE AND WILLIAM B. PIERCE, OF CHICAGO, ILLINOIS, ASSIGNEES TO
PIERCE WRAPPING MACHINE COMPANY, OF CHICAGO, ILLINOIS, A CORPORATION
OF ILLINOIS.

FOLDER DEVICE.

1,296,117.

Specification of Letters Patent.

Patented Mar. 4, 1919.

Original application filed August 7, 1911, Serial No. 842,635. Divided and this application filed January 2, 1915. Serial No. 803.

To all whom it may concern:

Be it known that we, FRANK M. PIERCE and WILLIAM B. PIERCE, citizens of the United States, and residents of the city of Chicago, county of Cook, and State of Illinois, have invented certain new and useful Improvements in Folder Devices; and we do hereby declare that the following is a full, clear, and exact description of the same, reference being had to the accompanying drawings, and to the numerals of reference marked thereon, which form a part of this specification.

This application constitutes a division of our patent for wrapping machine, No. 1,158,278, issued Oct. 26, 1915. However, in the present instance we have shown the folder of the type illustrated and claimed in the said patent as associated with a 20 slightly different type of shuttle, but this is immaterial, as the folder is adapted for use in any manner wherein it is desired to fold a continuous strip of paper drawn therethrough.

25 It is an object therefore of this invention to construct a folder device for attachment upon a shuttle which is rotated about a body to be wrapped to apply a spiral wrapping thereon with the edge of the wrapper folded 30 and thus made of double thickness as applied upon the article.

It is also an object of this invention to construct a pivotally mounted folder device mounted at an angle upon a suitable pintle 35 secured between the side walls of the shuttle, capable of movement to permit the paper to be drawn therethrough and therefrom for proper application of the paper to an article being wrapped.

40 It is furthermore an important object of this invention to provide a construction wherein paper is drawn from a hollow shuttle and passed through a suitable tension means and then through a pivotally mounted 45 folding device which serves to fold the paper as it is drawn therethrough for application to the article, so that the exposed edge of the wrapper upon the article is of double thickness.

50 It is finally an object of this invention to

construct a simple folder device pivotally mounted and inclined within the walls of a shuttle to receive the wrapping material drawn therethrough, folding the same for application upon an article to be wrapped. 55

The invention (in a preferred form) is illustrated in the drawings, and more fully pointed out and defined in the appended claims.

In the drawings:

Figure 1 is a central, vertical section taken through a shuttle equipped with a folder embodying the principles of our invention and illustrating a coil of wire receiving a wrapping applied thereto, the strips of 65 wrapping material passing through said folder device.

Fig. 2 is a section taken on line 2—2 of Fig. 1, with parts shown in elevation and with the object being wrapped illustrated 70 in dotted lines.

Fig. 3 is a fragmentary detail section taken on line 3—3 of Fig. 2.

Fig. 4 is a detail section taken on line 4—4 of Fig. 2.

Fig. 5 is an end view of the folder device looking toward the exit end thereof.

Fig. 6 is a fragmentary detail section taken on line 6—6 of Fig. 2, illustrating the angled mounting of the folder device looking at the 80 entrance end thereof.

As shown in the drawings:

The shuttle comprises two section members articulated together and affording therein a compartment to receive the wrapping material, consisting of apertured side wall members 1 and 2, articulated together at their meeting ends by means of a rivet 3, secured therethrough to afford a pintle. Said side walls are connected transversely by means 85 of webs or plates 4 and 5, respectively, affording one end of the carton compartment, and also by means of transverse pins or rivets 6, on diametrically opposite sides of the shuttle, which hold the side walls of 95 the shuttle spaced equal distances apart, and which also serve to secure thereto the lower half 7, of the sheet metal outer peripheral wall for the shuttle sections.

As shown also, the meeting ends of the 100

shuttle sections are provided with transverse end walls 8 and 9, respectively, which register against each other when the shuttle is closed, and are each provided with registering apertures, through which extends a spring pressed latching bolt 10, secured upon one of the shuttle sections. Said bolt 10, is pivotally engaged upon a suitable pintle 11, extending through the shuttle sections and is normally held in engaging position by means of a spring 12, which bears on the free end or tail of said bolt, as clearly shown in Fig. 2.

Approximately half the outer peripheral wall for the shuttle is hinged to open outwardly therefrom to permit the insertion of wrapping material X in the folded half, as shown in Fig. 2. For this purpose short hinge sections 13, are engaged upon each of the pintles 6, and are each connected by means of pintles 14, with longer peripheral wall sections 15 and 16, respectively. The section 15, is provided with a tongue 17, adapted to pass through a corresponding slot in the outer end of the peripheral wall section 16, and to rest upon a transverse bar 18, secured across said slot on the inner side of said wall section at the extremity thereof.

A bolt 19, is slidably engaged on the inner side of said wall section 16, and at its outer end is curved outwardly and upwardly to engage over the tongue 17, on the plate 15. As shown, pulling springs 20, are secured upon said bolt, one of which is shown in the sectional view and on the rigidly secured transverse bar 18, and act to hold said bolt 19, forwardly or in engaging position, and finger apertures are provided through both of said wall sections 15 and 16, adjacent said bolt, to permit the retraction of the bolt to release said wall sections the one from the other.

Said shuttle is provided on its forward side wall with a peripheral rim or flange 21, which assists in supporting the same when the shuttle is used in the wrapping machine. Said shuttle is also provided with a corresponding flange or rim 22, on its rear wall for the same purpose, and formed integral therewith is a gear 23, of substantially the same diameter, by which the shuttle is driven when used in the machine, said gear, of course, being constructed in two sections corresponding to the respective sections 1 and 2, of the hollow shuttle. Each of the respective shuttle sections 1 and 2, are provided with inner peripheral walls 24 and 25, respectively.

As shown, parallel guide rollers 26, are provided near the hinge connection in the inner peripheral wall 25, of the shuttle near the abutting end of said inner walls, and between which the paper strip or other wrapping material X, is fed outwardly from

within the shuttle. A filler or bridge member 65 is provided to prevent any portion of the wrapping material fouling with the opening and closing of the shuttle by becoming caught between the hinged portions of the shuttle when the same is opened. For this purpose a transverse bar or plate 27, is secured flush with the inner wall 25, in close relation with said guide rolls, and secured thereon is a spring plate or bridge member 28, which extends within the other shuttle 75 section and bears upon the inner surface of the wall 24, thereof, as clearly shown in Fig. 2, so that when the shuttle opens, the package of wrapping material within the shuttle is supported upon said bridge member. Within a compartment or space provided therefor at the end of the shuttle section from which wrapping material is drawn, as clearly shown in Fig. 2, is a tension device for the wrapping material, and a folding mechanism for folding the same longitudinally before the material is applied to the body being wrapped.

Said tension device comprises a spring plate 29, secured transversely in the end of the shuttle section 2, being free at its outer extremity, and pivotally engaged upon a pintle 30, extending through the side walls of said shuttle section 2, is an adjustable lever 31, the outer end of that directed toward and bearing upon the free extremity of said spring plate 29, having a roller 32, journaled thereon. The adjusting mechanism for said lever 31, comprises an angular sleeve 43, secured to the inner end of the lever into which extends a wedge member 44, comprising a nut threaded on a screw shaft 45, extending through the side walls of the section and provided with a head at one end shaped to be engaged by a suitable tool to rotate said screw to adjust the wedge inwardly or outwardly and thereby swing the outer end of the lever toward or from the spring plate 29.

As shown a leaf spring 46, is engaged at 110 its ends on said shaft and bears at its middle portion against the inner end of the levers and tends at all times to hold the inner end of the lever outwardly from the wedge as indicated in Fig. 7. Pivotally engaged in the end of the shuttle section 2, adjacent the roller 32, of the tension device, is the folder for the wrapping material. This comprises, as shown, a plate 33, engaged at one end on a suitable pin or pintle 34, secured to the side walls of the shuttle sections and curved outwardly from the roller 32, and directed inwardly toward the article to be wrapped. Integrally connected with said plate 33, at one side thereof, is a guide plate 35, of sufficient width at the receiving end thereof to receive the paper therein at its full width, and tapering toward its other extremity to

afford a narrow restricted nozzle, and turned at its free edge at 35° over the plate 33, to bend or fold the wrapping material thereover as it is drawn therethrough. At the 5 exit or tapered end of the folder device said plate 33, is cut away as indicated by the reference numeral 36, and a large rectangular aperture 37, is cut in said plate member 35. The purpose of cutting away said plate 33 at 36 is to permit the turned over end 35° to be brought into close proximity to the plate 35, whereby the discharge end of this device will be of such narrow compass, as shown in Fig. 5, as to cause the paper not only to be 10 folded in its passage therethrough, but also to be creased. It will be obvious that if the plate 33 were not cut away at 36, it would be impossible to bring the end 35° sufficiently close to the plate 35 to accomplish this result. Said pintle 34, is mounted in an inclined position between the side walls of said shuttle section 2, as clearly shown in Figs. 3, 4, and 6, the inclination thereof being in two directions, the one as shown in Figs. 25 3 and 4, to tilt the exit end of the folder device upwardly, and the other inclination serving to cant the folder device to one side, as clearly shown in Fig. 6. A ferrule or bushing 38, is mounted upon said pintle 34, 30 above the connection of the folder thereto.

Within a corresponding compartment in the other shuttle section 1, a wire spool or bobbin 39, is journaled, and adjacent thereto is a tension roller 40, provided with a central groove thereon about which the wire may be turned one or more times to afford the requisite tension before being applied to the article being wrapped. A small cutter 41, is provided at the end of the shuttle 40 section 2, adjacent the folder and is fitted upon the end wall 9, in convenient position to permit the wrapping material to be pressed thereagainst to sever the same when a wrapping operation is completed.

The operation is as follows:

When the shuttle is used in a machine, it is first rotated into the position shown in Fig. 2, and the belt 10, unlatched by thrusting any suitable tool or instrument through the aperture 42, provided in the wall 7, of the shuttle section and the respective shuttle sections 1 and 2, may be swung into an open position about the pintle bolt 3. The article Z to be wrapped, is then inserted into the 55 shuttle, as shown in Fig. 4, and the shuttle closed, whereupon after starting the paper strip X, on the article, the shuttle is rapidly rotated to wind the strip upon the article, as clearly shown in Fig. 1.

60 The paper is fed outwardly from within the shuttle between the respective rollers 26, thence through the tension mechanism, to the folder 33, and then to the article Z, being wrapped. Owing to the high speed of

rotation of the shuttle, the package of wrapping material X, therein, is thrown outwardly by centrifugal action, relieving all pressure from the inner folds from which the paper is drawn, thus obviating any tendency to tear the paper. The paper passes 65 around the tension roller 40, and thence through the folder before described, and the paper is thereby folded longitudinally so that the outer edge of the spirally wrapped strip is of double thickness as applied to the coil or other annular body. The tilt to the pivotally mounted folder device upon the inclined pintle 34, assures a proper directing of the strip proceeding therefrom to the article being wrapped.

As already pointed out, said pintle 34, is inclined in two directions, one to tilt the exit end of the folder device upwardly, and the other inclination serving to cant the folder laterally to one side, as shown clearly in Figs. 3 and 6, respectively. The wrapping having been completed, the machine 70 on which the shuttle is mounted is stopped and the wrapping strip is severed by pressing the same against the cutter element 41, 75 whereupon the shuttle is opened as before described and the wrapped article removed from the machine.

The wire from the wire bobbin 39, leading around the tension roller 40, may or may 80 not be applied to the article coincidently with the application of the folded paper strip, as desired. The construction of the shuttle permits a maximum quantity of wrapping material to be contained therein to 85 enable a large number of objects to be wrapped without refilling the shuttle, and furthermore, inasmuch as the wrapping material is withdrawn from the inner side of the package of folded material, no resistance to 90 withdrawal is exerted by the weight of the paper in the shuttle. The paper is inserted into the shuttle already folded by releasing the slidable belt 12, and swinging the hinged sections 15 and 16, outwardly 95 thus affording unobstructed access to the interior of the shuttle.

When the shuttle is opened to permit insertion or removal of an article to or from the machine, the bridge member 28, which 100 is secured to the inner wall of one of the shuttle sections, is drawn along the inner wall of the other shuttle section to bridge the gap between said shuttle sections and support the inner layers of wrapping material thereon, preventing the same becoming 105 pinched therebetween when the shuttle is again closed. In the particular type of high speed machine with which this shuttle is adapted for operation, the folder device 110 herein described and illustrated, is peculiarly adapted for the most efficient application of the strip to the article. It is obvious, how-

- ever, that numerous variations and modifications in the construction may be made without departing from the principles of this invention, and that the folder used, is adaptable for many different kinds of material and for many different purposes. We therefore do not purpose limiting the patent granted otherwise than necessitated by the prior art.
- 10 We claim as our invention:
1. In a wrapping machine of the class described, the combination of a tension device comprising spring impelled contacting members, and a folding device pivotally connected near one of said members.
  2. In a device of the class described, the combination of a tension member, and a folding member pivotally mounted adjacent said tension member to receive a wrapping strip directly from the tension member.
  3. In a device of the class described, the combination of a pivoted tension member, and a folding device connected to move in conformity with the path of material therethrough.
  4. In a device of the class described, the combination with a shuttle, of a pintle bolt mounted in inclined position therein, and a folder device pivotally mounted thereon extending transversely of the shuttle and tilted longitudinally and caused laterally with respect to said shuttle to insure proper application of a strip of paper fed therethrough to an article.
  5. A folder of the class described, embracing the combination of a folder plate, and a pivotal mounting therefor comprising a pintle bolt mounted in a shuttle inclined longitudinally and transversely of said folder.
  6. In a device of the class described, a pivoted tension member, and pivotally mounted folding means adjacent thereto.
  7. In a device of the class described, the combination with a shuttle, of a paper folder comprising a plate, and a guide plate integral therewith tapered toward its discharge end to provide a restricted nozzle, said guide plate having its free end turned over the plate to fold the wrapping material as it is drawn therethrough.
  8. In a device of the class described, a shuttle, and a folder comprising a sheet of metal bent to afford a tapering nozzle thereon, said nozzle comprising an inner narrow fold, an outer wider fold and a lip integral with the outer fold and turned over the inner fold.
  9. In a device of the class described, a shuttle, and a paper folder attached thereto and comprising a tapered nozzle and a member coacting therewith for folding the paper as it passes through the nozzle.
  10. In a device of the class described, an annular shuttle, and a folder pivoted thereto adapted to oscillate on its pivot and adapted to tilt in a direction at an angle to the feed of paper to the article wrapped.
  11. In a device of the class described, the combination with an annular shuttle, and an article to be wrapped, of a paper folder pivoted to the shuttle and adapted to swing on its pivot to feed the folded paper uniformly to varying sizes of articles and to tilt the paper as it is fed to the article to be wrapped.
  12. In a device of the class described the combination with a shuttle, of a folding device pivoted to tilt in a plurality of directions and operated by the tension of the wrapping material to properly position itself to apply the wrapping properly to articles with surface inequalities.
  13. In a device of the class described, the combination with a shuttle of a folder mounted to tilt in a plurality of directions.
  14. In a device of the class described, the combination with a shuttle carrying wrapping paper, and an annular article to be wrapped rotatable through the eye thereof, of a folding device mounted on the shuttle and automatically adjustable by the tension of the paper to properly position itself to feed the paper to the article wrapped.
  15. In a device of the class described, the combination with an annular shuttle, and an article to be wrapped, of a folder pivoted to the shuttle and adapted to automatically position itself by the tension of the wrapping paper and the position said paper assumes on the article wrapped.
  16. A folding device of the class described, comprising a pivotally mounted member, and a folding means thereon adapted to align itself with the line of feed of paper fed therethrough to be folded thereby.
  17. In a device of the class described, the combination with a shuttle, of mechanism movably mounted thereon acting automatically to align itself with the line of feed of paper fed therethrough and to be folded thereby.
  18. In a device of the class described, the combination with a shuttle of a folder plate member pivotally mounted thereon at an angle thereto.
  19. In a device of the class described, the combination with a shuttle, of unitary folding, guiding and creasing means adjustably secured at an angle thereto.
  20. The combination with a shuttle, of a pivotally mounted folder plate thereon, the pivotal axis thereof inclined in two different directions with respect to the shuttle.
  21. In a folder device for a wrapping machine shuttle, a pintle bolt mounted in an inclined position on the shuttle, a plate pivotally mounted thereon, and a guide plate integral therewith adapted to fold the wrapping material.

22. In a device of the class described, a
pintle bolt mounted in an inclined position,
a plate pivotally mounted thereon, a guide
plate integral therewith tapered to afford a
5 narrow restricted nozzle, and having one
edge turned over said plate to fold wrapping
material thereover as it is drawn through
said guide plate.

In testimony whereof we have hereunto
subscribed our names in the presence of two 10
subscribing witnesses.
